UNITED STATES PATENT OFFICE.

HARRY S. VROOMAN, OF CHICAGO, ILLINOIS.

SCREENING AND SEPARATING MACHINERY.

1,067,204.

Specification of Letters Patent.

Patented July 8, 1913.

Application filed August 8, 1911. Serial No. 642,930.

To all whom it may concern:

Be it known that I, HARRY S. VROOMAN, a citizen of the United States, residing at Chicago, in the county of Cook and State of Illinois, have invented a certain new and useful Improvement in Screening and Separating Machinery, of which the following is a full, clear, concise, and exact description, reference being had to the accompanying drawings, forming a part of this specification.

My invention relates to screening and separating machinery and has for its object the provision of a new and improved machine of this general character.

In one form of its employment, my improved machine is of great use in connection with the screening and separating of sand or other such similar material, although of course, my invention is not so limited. I show however, herein and describe one specific form of carrying out my invention and in this particular form the machine which is constructed in accordance with my invention is particularly adapted for thus screening and separating sand or similar material, and I will describe my invention in connection with such a particular machine having it understood of course, that in thus describing it, I am not limiting it as this application sets forth merely one of the forms which my invention may take. I will also use the word sand herein to signify material in general for which the machine herein may be satisfactorily employed.

In the general form of the machine shown herein, I utilize crusher rolls, an adjustable chute and a plurality of screens which may be of the same or different size mesh, and by means of which the sand is screened and separated.

My improved machine contemplates the mounting of the screening devices in such a way that they are agitated in a novel manner to secure the most efficient screening effect and at the same time insure the progressive movement or discharge of sand that remains as residue. The machine may be operated through any suitable power agency or manually if desired, a suitable power motor being herein shown by way of illustration. The machine is arranged in such a way that it is portable. The claims herein are limited to the machine without the rolls or crushing devices as claims covering the combination of the screens and crushing

devices have been made the subject matter of a co-pending application Serial No. 650,214, filed Sept. 19, 1911.

My invention also contemplates a great many novel constructional features and arrangements, such for instance as the removable mounting of screening devices within suitable screen frames, all as will appear more clearly from the detailed description of one embodiment of my invention which will now follow in connection with the accompanying drawings illustrating this embodiment, in which:

Figure 1 is a longitudinal sectional view of my machine; Fig. 2 is a sectional view on lines *a—a* of Fig. 1; Fig. 3 is a partial end view looking toward the right of Fig. 2; Fig. 4 is a partial end view looking toward the left of Fig. 2 with the motor removed; Fig. 5 is a perspective view of one of the screens and screen carriers; Fig. 6 is a detail view of a portion of a screen; Fig. 7 is a detail view of a portion of the driving mechanism and the rolls of the machine, and Fig. 8 is a detail of construction.

Referring to the illustrations, I show a framework consisting of the two vertically arranged side members 1 and 2 which are held together by cross strips 3, 4, 5 and 6. A transverse plate 7 is provided to hold a motor 8, if such is employed, which motor by means of the belt 9 drives the mechanism as will be suitably explained hereafter. The front legs of the machine are provided with rollers 10 and the rear legs are provided with handles 11 so that the machine is portable and may be rolled from place to place.

A movably mounted screen frame 12 is provided in the upper portion of the machine and between the side frames 1 and 2 and is provided with bearing plates 13 to which are rotatably mounted links 14 on pins 14^a, each link being rotatably mounted on a stud 15 secured in the side frames. The right hand extremity of the screen frame also carries bearing plates 16, which by means of studs 17 are rotatably supported upon the upper extremities of rocker arms 18. These rocker arms are supported upon studs 19 in the side frames of the machine. The lower extremities of the rocker arms 18 carry by means of rotatably mounted studs 20 suitable bearing plates 21, which bearing plates are fastened to a second screen frame 22, at or near the right hand extremity thereof. The left hand extremity of this second screen

frame carries two supporting plates 23 which are pivotally associated with links 24, which links are pivotally mounted in the side members 1 and 2 by means of the studs 25. It will thus be seen that if the rocker arms 18 are moved to and fro that the screen frames 12 and 22 are oppositely agitated, namely that they are moved from right to left and vice versa, and that their extremities are also given a slight up and down motion in connection with this horizontal motion. This peculiarity of the motion thus imparts to each extremity of each screen frame a rotary motion respectively about the studs 15 and 19 in the case of the screen frame 12 and about the studs 25 and 19 in the case of the screen frame 22. The arrangement is also such that while one extremity of the screen frame is receiving its upward motion, the other extremity is receiving its downward motion. A very efficient motion is thus secured for properly agitating the material to be screened. The screen frames 12 and 22 are likewise given the necessary tilt so that as the material is being screened the residue moves across the face of the screen toward the lower extremity thereof to be therefrom ejected in the course of the movement of the said frame. The rocker arms receive their motion by means of connecting rods 27 which are connected to suitable cranks 28 carried by the shaft 29 which is mounted in suitable bearings. This shaft 29 carries at one extremity a suitable pulley 30 which is engaged by the belt 9 and through the agency of which the machine in its entirety is driven. At its opposite extremity the shaft 29 carries a gear wheel 31 which meshes with suitable gear wheels 32 and 33 respectively mounted on shafts 34 and 35. The shafts 34 and 35 are mounted in suitable bearings 36 and 37 respectively whose position is governed and adjusted by springs 38, 39. The shafts 34 and 35 carry rolls 39 and 40 respectively and these rolls are mounted as shown for a purpose which will presently appear although these rolls form no part of my present invention. An adjustable chute 41 is pivotally mounted at 42 and can occupy the position shown in full lines in Fig. 1 and also the alternative position shown in dotted lines in the same figure. This chute when occupying the position shown in full lines in Fig. 1 directs the refuse or residue which is cast away from the screen frame 12 between the crusher rolls 39 and 40 when such rolls are used, where this residue may be crushed and then deposited into the screen frame 22. When no rolls are used the rejected material is of course in that case deposited directly upon the screen frame 22. The screen frame 12 has a screen 43 and the screen frame 22 has

85 a screen 44. The material which passes

through the screen 43 falls onto the screen 44 and is further directed toward the upper lefthand portion of said screen 44 by means of a baffle plate 45 mounted on the framework as shown. The screen frames 12 and 22 consist of two side members and an end member, the lowermost extremity of said screen frames being open as shown so that the material left on the screen after screening may pass off from the screens 43 and 44 respectively. The side and end members of these screen frames are each provided with flanges 50 to support the screens 43 and 44 and to provide the necessary strengthening of the screens, cross members 46 are employed as shown on which the screens rest. The screens themselves consist of a net work 47 suitably bound at their ends and sides by the angle plates 48 and rivets 49. The screens themselves are thus bodily removable from the frame for purposes of interchanging or repair as the case may be. The method of removal is illustrated in Fig. 5 by the dotted lines.

The general operation of the machine will thus be apparent. The material to be separated and screened is placed within the screen frame 12 upon the screen 43. The motor 8 is started in operation, thereby oscillating the rocker arms 18 and causing a suitable oscillatory motion of the frames 12 and 22 carrying the screens 43 and 44. Some of the material falls through the screen 43 and is directed by means of the baffle plate 45 onto the second screen 44, which second screen 44 may be of finer mesh than the screen 43. The material is again sifted by the screen 44 and the fine siftings are deposited within the receptacle 51. The residue from the screen 44 is thrown out from the screen frame 22 into a receptacle 52. The material within the receptacle 52 is of course fine enough to have passed through the screen 43 and there are thus two sizes of screenings, those within the receptacle 51 and those within the receptacle 52. A third grade of screenings of larger size have been thrown off from the screen 43 and these may be suitably collected outside of the machine if the chute 41 be in the position shown in dotted lines. If the chute is in the position shown in full lines in Fig. 1, then this coarse material which leaves the screen 43 is directed by means of the chute 41 between the rolls 39 and 40 and is crushed by these rolls and deposited upon the screen 44, or is deposited directly upon said screen if no rolls are used, in a more finely divided condition so that it may be again sifted. It will thus be seen that my improved machine separates the original material and provides means to segregate the coarse particles so that they may be available for further screening and sifting by the screen 44.

While I have herein shown and particu-

larly described one embodiment of my invention, I do not mean to limit myself to such specific description and illustration, but

Having thus described one form of carrying out my invention, what I claim as new and desire to secure by Letters Patent is:

1. The combination with a plurality of screens, a swinging link support for one extremity of each of said screens, a rocker arm to support and pivotally mount the other extremities of each of said screens, said screens sloping from their rocker arm mounting so as to converge.

2. The combination with a plurality of screens, a swinging link support for one extremity of each of said screens, a rocker arm to support and pivotally mount the other extremities of each of said screens, said screens sloping from their rocker arm mounting so as to converge, said links being respectively shorter than the rocker arm.

3. In a machine of the character described, the combination with a plurality of movable screens, pivotal mountings for one extremity of each of said screens, a rocker arm for the remaining extremity of each of said screens for oscillating said screens, means for directing the material passing through one screen to the other screen, and means for directing the material rejected by the said first screen toward the second screen aforesaid.

4. In a machine of the character described, the combination with a plurality of movable screens, movable mountings for one extremity of each of said screens, a rocker arm for the remaining extremity of each of said screens for oscillating said screens, means for directing the material passing through one screen to the other screen, and means for directing the material rejected by the said first screen toward the second screen aforesaid.

5. The combination of a plurality of screens, a swinging link support for one extremity of each of said screens, a rocker arm associated with the other extremities of said screens for oscillating said screens, means for directing the material passing through one screen to the other screen, and means for directing the material rejected by the said first screen toward the second screen aforesaid.

6. The combination of a plurality of screens, a swinging link support for one extremity of each of said screens, a rocker arm associated with the other extremities of said screens for oscillating said screens, means for reciprocating said rocker arm, means for directing the material passing through one screen to the other screen, and means for directing the material rejected by the said first screen toward the second screen aforesaid.

65. 7. The combination with a plurality of

screens, a swinging link support for one extremity of said screens, a rocker arm associated with the other extremities of said screens for oscillating said screens, means for reciprocating said rocker arms, said rocker arms being pivotally supported intermediate their ends and having means at their opposite extremities for pivotal association with said screens, means for directing the material passing through one screen to the other screen, and means for directing the material rejected by the said first screen toward the second screen aforesaid.

8. In a machine of the class described in combination with a plurality of screens, means for oscillating said screens, a baffle plate for directing the material passing through one screen toward one extremity of the other screen, and means for directing the material passing through the first screen aforesaid toward the second screen aforesaid.

9. A machine of the character described comprising two vertically arranged side members with a movably mounted screen frame in the upper portion, and a movably mounted screen frame in the lower portion between the side frames, a chute for directing material passing through the first screen to the second screen and means for directing material rejected by the first screen toward the second screen.

10. In a machine of the character described in combination with a plurality of screens, means for oscillating said screens, means whereby the material passing through one screen falls upon the second screen, and means for directing the material rejected by said first screen toward the second screen.

11. In a machine of the character described the combination with a plurality of screens, means for oscillating said screens, means for mounting said screens one above the other so that the material passing through the upper screen falls upon the lower screen, and means whereby the material rejected by the first screen falls upon the second screen.

12. In a machine of the character described the combination with a plurality of screens, means for oscillating said screens, means for pivotally mounting said screens one above the other so that the material passing through the upper screen falls upon the lower screen, and means whereby the material rejected by the first screen falls upon the second screen.

13. In a machine of the character described, the combination with a plurality of screens, means for pivotally mounting one extremity of each of said screens, a rocker arm for pivotally mounting the opposite extremities of said screens, said rocker arm being pivoted between said screen mounting points, said screens sloping toward each

other from said rocker arm and means for directing material rejected from the upper screen to the lower screen.

14. In a machine of the character described the combination with a plurality of screens, of a movable chute for directing material rejected by one screen toward the other screen, said chute when moved to its alternative position directing said rejected material away from the said second screen said screens being located one above the other so that the material falling through the upper screen may fall onto the lower screen.
15. 15. In a machine of the character described the combination with a plurality of

screens, one above the other, so that the material falling through the upper screen falls upon the lower screen, means for directing material passing through the upper screen toward the lower screen, and an adjustable chute for directing rejected material from the first screen toward the second screen, said chute when in its alternative position directing said rejected material away from said second screen.

In witness whereof, I hereunto subscribe my name this 31st day of July A. D., 1911.

HARRY S. VROOMAN.
